Primary Examiner — Michael A Maharajh

(57) **CLAIM**

The ornamental design for a percussive massage device, as shown and described.

DESCRIPTION

FIG. 1 is a front perspective view of a percussive massage device, according to an embodiment;

FIG. 2 is a front view of the percussive massage device, according to an embodiment;

FIG. 3 is a rear view of the percussive massage device, according to an embodiment;

FIG. 4 is a left side view of the percussive massage device, according to an embodiment;

FIG. 5 is a right side view of the percussive massage device, according to an embodiment;

FIG. 6 is a top view of the percussive massage device, according to an embodiment;

FIG. 7 is a bottom view of the percussive massage device, according to an embodiment; and,

FIG. 8 is a rear perspective view of the percussive massage device, according to an embodiment.

The broken lines showing portions of the percussive massage device form no part of the claim.

1 Claim, 8 Drawing Sheets
